UNITED STATES PATENT OFFICE

WILLIAM WARD DAVIDSON, OF EVANSTON, ILLINOIS, ASSIGNOR TO DAVIDSON MANUFACTURING COMPANY, OF CHICAGO, ILLINOIS, A CORPORATION OF WISCONSIN

FOLDING MACHINE

Application filed May 1, 1931. Serial No. 534,297.

This invention relates to folding machines designed and adapted for holding sheets of paper and the like, and has particular reference to such machines, in which folding is effected by means of what are known to the trade as buckle chutes mounted in association with suitable feeding and folding rollers.

A primary object of the invention is to provide folding mechanism of the general type specified, in which the adjustable stops mounted on the buckle chute are adapted to be moved into close proximity to an intermediate roller, so as to close the space in the buckle chute which receives the paper, the sides of said stops proximate said roller being curved, preferably in such manner that when said stops are at the contemplated limit of their adjustment towards said roller, said surfaces will be substantially concentric with the surface of the roller and will form guides which will operate to discharge sheets from said folding mechanism or unit in the same condition as they are delivered thereto, that is, without receiving a fold therefrom.

A further object of the invention is to provide improved means for accurately adjusting the width of the spaces between the rollers of the folding mechanism to adapt it for operating on sheets of different thicknesses, and for securing said rollers in adjusted positions.

To effect the objects thereof, a folding mechanism embodying my invention and improvements comprises the various features, combinations of features and details of construction hereinafter described and claimed.

In the accompanying drawings, in which the invention is fully illustrated,

Figure 1 is a side view of a buckle chute folding mechanism or unit embodying my invention and improvements.

Figure 2 is a top plan view of the mechanism shown in Figure 1.

Figure 3 is a sectional elevation on a somewhat enlarged scale, taken substantially on the line 3-3 of Figure 2, the mechanism being shown in operative relation to effect folding of sheets delivered thereto.

Figure 4 is a view substantially similar to Figure 3, but showing the mechanism adjust-

ed to close the buckle chute and to discharge sheets delivered to said mechanism without receiving a fold.

Figure 5 is a somewhat enlarged bottom plan view of the buckle chute substantially from the position 5-5, Figure 3.

Figure 6 is a sectional view substantially on the line 6-6 of Figure 3.

Figure 7 is an enlarged, fragmentary, detailed view.

Figure 8 is an enlarged, fragmentary view substantially from the position 8-8, Figure 2.

Figure 9 is a sectional view substantially on the line 9-9 of Figure 8; and

Figure 10 is a fragmentary, sectional, plan view on the line 10-10 of Figure 8.

Describing the invention with reference to the drawings, A designates as a whole, a folding mechanism or unit of the buckle chute type, embodying my invention and improvements, shown as operatively mounted on the frame *a* of a folding machine of which it forms a part.

Described, generally, 1, 2 and 3 are the sheet feeding and folding rollers of the mechanism or unit A, and B designates the buckle chute thereof, as a whole.

As regards their usual features and excepting as hereinafter particularly described and pointed out, the construction, manner of mounting and also the operation of said folding mechanism or unit and of the constituent parts thereof, are old and well known and will be clearly understood and can readily be supplied by mechanics familiar with the construction and operation of such mechanisms from an examination of the drawings, without a description thereof in detail.

In the drawings, *b* designates a sheet of paper or the like on which the mechanism A is operating.

In accordance with usual practice, the buckle chute B is provided with stops 4 for the sheet of paper *b* or the like, said stops being secured to a relatively thin metal bar 5, which is slidably fitted to a space 6 formed between the top and bottom plates 7 and 8 of said buckle chute. Said stops 4 are positioned in slots 9 formed in the plates 7 and 8 so as to be adjustable towards and from the

roller 2, and are adapted to be secured in adjusted positions therein by means provided for the purpose, presently described.

In accordance with my invention, I attain the object thereof as it relates to preventing sheets *b* delivered to said folding unit, from passing into the space 6 in the buckle chute B and also, as it relates to guiding said sheets through the folding mechanism without being folded, in the following manner:—

The slots 9, in which the stops 4 are positioned, are extended at their ends adjacent the roller 2 so that they will be open, as shown in Figures 2 to 4, and the sides of said stops adjacent said roller 2 are curved, as shown at 10, Figures 3 and 4, the relation being such that said stops may be advanced towards the roller 2 so that they will project beyond the lower ends of the plates 7 and 8 of the buckle 20 chute B, and the sides of said stops proximate said roller 2, being substantially concentric with the surfaces of said roller when at the contemplated limit of their advancement towards the same, as clearly shown in Figure 25 4 of the drawings, the curved faces of said stops being so proportioned that they will extend slightly above a sheet *b* delivered to the rollers 1 and 2, whereby the advancing edge of said sheet will strike the curved surfaces 10 of said stops and be guided thereby between the rollers 2 and 3 and thus discharge from the folding mechanism or unit A without being folded.

In the preferable construction shown, the bar 5 which carries the stops 4 is adapted to be adjusted and secured in different adjusted positions by means as follows:—Rotatably mounted in lugs 11 adjacent opposite sides of the main frame of the buckle chute B are screws 13 and secured to the opposite ends of the bar 5, preferably in such manner as to permit limited play thereof endwise of said bar, are blocks 14 pivoted between their ends at 15 to the undersides of which, respectively, are bars 16, formed at the opposite ends of each of which are segmental nuts 17 and 18, the threads of said nuts and of the screws 13 being of the same pitch and the bars 16 being mounted in such position that pivotal movement of said bars 16 in opposite direction will effect engagement and disengagement of said segmental nuts with and from the screws 13, said segmental nuts being maintained yieldingly in engagement with the screws 13 by means of compression springs 19, the ends of which are confined in holes or recesses formed in the blocks 14 and in opposed parts of the pivoted arms 16.

The arms 16 are adapted to be turned 60 against the force of the springs 19 applied thereto by means of finger grips 20 and 21.

As shown, the blocks 14 are mounted on the ends of the bar 5 in the following manner:—For convenience in operation, the ends of said bar 5 are offset, as shown at 22, Figure 5, and

formed in the ends of said offset portions are slots 23, the edges of which are slidably fitted to corresponding grooves formed in the blocks 14. In practice, desired play or endwise movement of the blocks 14 on the bar 5 is limited by the projection ends 24 of the bar 5 at corresponding sides of the slots 23, which are bent slightly out of line with the main portion of said bar 5, thus causing them to bind in the grooves in the blocks 14, which the edges of the slots 23 engage.

When it is desired to effect any considerable adjustment of the stops 4, this can quickly and conveniently be done by grasping the finger grips 20 and 21 and pressing them together against the force of the springs 19, thus turning the bars 16 pivotally to disengage the nuts 17 and 18 from the screws 13, and releasing the bar 5 and permitting it to be moved manually either towards or from the roller 2. When the bar 5 is in position corresponding approximately to a contemplated adjustment of the stops 4, the finger grips 20 and 21 are released, thus permitting re-engagement of the nuts 17 and 18 with the screws 13, final, accurate adjustment of said stops being effected by means of the screws 13.

In accordance with my invention, each of said screws is adapted to be turned separately to effect adjustment of opposite ends of the bar 5 and is held frictionally in position corresponding to a desired adjustment, by means as follows, see particularly Figure 7:—Threaded to the ends of the screws 13 which project above the lugs 11 of the buckle chute frame are thumb nuts 25, the body portions of which comprise reduced portions 26 fitted to turn freely in holes formed in said lugs 11. The reduced portions 26 of said thumb nuts 105 are longer than the thickness of the lugs 11 so that they will project through and below said nuts and threaded to the screws 13 below the lugs 11 are lock nuts 27 adapted to bear against the projecting lower end 26 of the thumb nuts 25, thus causing both the thumb nuts 25 and the lock nuts 27 to turn with the screws 13. Also, the screws 13 are adapted to be secured frictionally in adjusted position by means of dished spring washers 28 inserted over the reduced portion 26 of the thumb nuts 25 and which react between the lock nuts 27 and the undersides of the lugs 11, the relation being such that when the lock nuts 27 are turned into firm engagement with the projecting lower ends of the thumb nuts 25, the dished washers 28 will be under desired tension.

In accordance with my invention, also, I attain the object thereof as it relates to accurately adjusting the rollers 1 and 3 relative to the roller 2 and for securing said rollers in adjusted position, by means as follows, see particularly Figs. 8 to 10:—The roller 2 is mounted in a bearing formed directly in the

frame *a* of the machine so as to rotate on a relatively fixed axis, while the rollers 1 and 3 are rotatably mounted in bearing blocks 29 respectively fitted to slots formed in the frame *a*, so as to be adjustable therein towards and from the roller 2, said bearing blocks being confined in their respective slots by flanges formed thereon, which embrace the frame *a* at opposite sides of said slots, in a usual manner.

The bearing blocks 29 are maintained yieldingly at the limit of their advancement towards the roller 2, corresponding to desired spacing of the rollers 1 and 3 relative to the roller 2, by springs 31 inserted between said bearing blocks and lugs 32 formed on the frame *a*, advancement of said bearing block being limited and retraction thereof against the force of the springs 31 being effected by screws 33 which have threaded engagement with holes in the bearing blocks 29, as shown, secured to the outer ends of which are heads 34 comprising body portions 35 adapted to bear on the lugs 32, handles 36 for turning said screws and disks 37 provided in their perimeters with teeth adapted for engagement by spring locking pawls 38. The springs 31 surround the screws 33 as guides and the spring pawls 38 are supported in position by brackets 39, which, as shown, are formed integral therewith and are secured to the frame *a* adjacent the lugs 32 by screws 40.

The threads of the screws 33 are of such fine pitch and the disks 37 of such large diameter and the teeth thereof of such small pitch that turning movement of said screws corresponding to the distance between adjacent teeth will effect a very fine adjustment of the rollers 1 and 3 relative to the roller 2, say .001 of an inch. This relation can, of course, be varied as desired.

I claim:

1. In folding mechanism, the combination of driven rollers, including spaced rollers and an intermediate roller co-operating with both of said spaced rollers, a buckle chute provided with slots which cut through the lower edge thereof, stops adjustably mounted in said slots with capacity for adjustment into close proximity to the intermediate roller thereby rendering the buckle chute inoperative, and means for adjusting said stops, the sides of said stops proximate said roller forming guides arranged for delivering sheets without folding them from a pair of receiving rollers directly to a pair of discharge rollers, said pairs of rollers, respectively, including different spaced rollers and the intermediate roller, which is common to both.

2. Folding mechanism as specified in claim 1, in which the guide faces of the buckle chute stops are curved.

3. Folding mechanism as specified in claim 1, in which the guide faces of the buckle chute

stops are substantially concentric with the surface of the intermediate roller when said stops are in their positions of extreme contemplated advancement.

4. Folding mechanism as specified in claim 1, in which the spaced rollers are mounted with capacity for adjustment towards and from the intermediate roller and which comprises means for separately effecting such adjustments and for yieldingly locking said adjustable rollers in position.

5. Folding mechanism as specified in claim 1, in which the spaced rollers are rotatably mounted in bearing blocks fitted to slots in the frame of the mechanism and are adjustable therein towards and from the intermediate roller, and which comprises means for separately effecting such adjustments and for yieldingly locking said bearing blocks in adjusted positions.

6. Folding mechanism as specified in claim 1, in which the spaced rollers are rotatably mounted in bearing blocks fitted to slots in the frame of the mechanism and are adjustable therein towards and from the intermediate roller, and which comprises means for separately effecting such adjustments and for yieldingly locking said bearing blocks in adjusted positions, consisting of screws having threaded engagement with holes formed in said bearing blocks, shoulders on which bear against rigid parts of the frame of the mechanism, springs applied to said bearing blocks in opposition to the action of said screws, disks secured to said screws provided with notches in their peripheries, and spring pawls having self-releasing teeth supported on the frame of the mechanism in position to engage the notches in said disks.

7. Folding mechanism as specified in claim 1, in which the means for supporting and adjusting the buckle chute stops and for securing said stops in adjusted positions comprises screws rotatably mounted at opposite sides of the buckle chute frame, nuts threaded to said screws the lower ends of which are shouldered and fitted to turn in bearings in fixed frame members and are proportioned to project through their bearings, lock nuts threaded to said screws below said fixed frame members arranged to lock said nuts to the screws to which they are threaded, and friction washers inserted between said lock nuts and the adjacent sides of said fixed frame members.

8. Folding mechanism as specified in claim 1, in which the means for supporting and adjusting the buckle chute stops and for locking them in adjusted positions comprises screws rotatably mounted in bearings at opposite sides of the buckle chute frame, a bar slidably supported on the buckle chute frame with capacity for adjustment towards and from the intermediate folding roller, arms pivoted between their ends at opposite ends

of said stop supporting bar so as to be movable therewith, segmental nuts on opposite ends of said pivoted arms arranged to engage the screws mounted at corresponding sides of the buckle chute, springs applied to said arms for maintaining said segmental nuts yieldingly in engagement with the screws with which they are associated, and manual means for turning said arms to disengage said nuts from said screws and for manipulating said stop supporting bar.

In witness that I claim the foregoing as my invention, I affix my signature this 18th day of April, 1931.

15 WILLIAM WARD DAVIDSON.
